(57) CLAIM

I claim the ornamental design of a can cover, as shown and described.

DESCRIPTION

FIG. 1 is a side view of a can cover, including a tip of a whipped cream can protruding from the top of the cover.

FIG. 2 is a top view of the can cover.

FIG. 3 is bottom view of the can cover.

FIG. 4 is a perspective view of the can cover as seen from the bottom; and,

FIG. 5 is a perspective view of the can cover as seen from the top.

The broken lines are for illustrative purposes only and from no part of the claimed design.
